Primary Examiner — David G Muller*(74) Attorney, Agent, or Firm* — Workman Nydegger(57) **CLAIM**

The ornamental design for a stabilizer, as shown and described.

DESCRIPTION

FIG. 1 is a perspective view of a stabilizer showing the new design;

FIG. 2 is a bottom perspective view thereof;

FIG. 3 is a top plan view thereof;

FIG. 4 is a right side elevation thereof;

FIG. 5 is a left side elevation thereof;

FIG. 6 is a bottom plan view thereof;

FIG. 7 is a front elevational view thereof; and,

FIG. 8 is a rear elevational view thereof.

The broken lines depicted in the Figures illustrate portions of the stabilizer that form no part of the claimed design.

1 Claim, 5 Drawing Sheets(56)
